UNITED STATES PATENT OFFICE.

FRANK J. O'BRIEN, OF BALTIMORE, MARYLAND, ASSIGNOR TO SOUTHERN CAN COMPANY, OF BALTIMORE, MARYLAND, A CORPORATION OF MARYLAND.

CAN CLOSURE.

Application filed October 22, 1921. Serial No. 509,474.

To all whom it may concern:

Be it known that I, FRANK J. O'BRIEN, a citizen of the United States, residing at Baltimore, in the State of Maryland, have 5 invented certain new and useful Improvements in Can Closures; and I do hereby declare the following to be a full, clear, and exact description of the same, reference being had to the accompanying drawings, 10 forming part of this specification.

This invention relates to a seam for a can closure including a removable gasket, and also to the method of producing such seam.

15 At the present time the sanitary seam, which is in almost universal use is open to one very serious objection, namely that the cover or head of the can must be destroyed in order to gain access to the contents. A great number of cans and containers utilizing gaskets have been proposed, and some few of these are so constructed that the gasket may be removed without injuring either the container or the cap, 20 permitting the use of the cap on the container after opening and until the contents of the container have been entirely consumed or used. But the seams with which I am familiar and which give this desired 25 result are expensive and difficult to manufacture.

It is the principal object of the present invention to provide a seam which may be formed cheaply and expeditiously and 30 which will so bind the gasket between the container and the closure that a perfect seal is formed and the cover united firmly to the body but at the same time by the removal of the gasket the cap or cover is 35 freed without injuring in any way the container or the cover.

A further object is to provide a closure which will not detract from the usefulness of the can as a container after the seal is 40 broken for the removal of the cover and part or all of the contents.

In the drawings illustrating the seam and the method of making it:

Figure 1 is a vertical section through a 45 wall of the container, a portion of the closure and through the annular gasket, as assembled.

Fig. 2 is a similar view showing the chuck and the first roller in position and showing

the container body flared after pressure has 55 been applied vertically to the cover.

Fig. 3 is a similar view showing the same chuck, but illustrating a finishing roller which fully seams the cover.

Fig. 4 shows a section through the seam 60 after the operation is complete.

The container body 10 is open at both ends and is cylindrical in form as is usual in the art. The cover 11 is provided with an annular strengthening rib 12 bounded on 65 the outside by a flat portion 14 which forms a valley between the rib 12 and the rim 15, the latter having an inwardly and downwardly directed flange 16. The rubber gasket 18 is glued or otherwise secured to 70 the flat under surface of the rim 15, preferably just out of contact with the inturned edge of the flange 16 so that when the cover is applied to the container the gasket will be spaced therefrom a slight distance as is 75 indicated at 19.

In Fig. 2 the chuck 20 is shown in contact with the valley 14 and with the nearly vertical portion 21. The roller 22 has advanced horizontally while the work is held by the chuck 20 and the vertical pressure against the cover causes the edge of the cover to be partially crimped against the rubber gasket. The roller 23 is now 80 brought into play and this roller fully seams the cover against the chuck 20 completing the seam shown in Fig. 4. The finished seam has a relatively narrow rim 15', a pronounced bead 25 and a cylindrical flange 16' parallel to the major portion of the 85 wall 26 of the container. The extreme upper portion of the container as at 27 has been bent outwardly to an angle of about 60 degrees and the portion 28 of the wall of the container just below this out turned flange is flared outwardly to a slight extent, the advantage of this structure being that when the gasket and cap are removed from the can there is no danger of cutting one's 90 hands while reaching within the container. 95

The seam formed in accordance with the method herein outlined has been found in practice to be extremely useful. In order to pull or blow the cap off by internal pressure it would be necessary to shear the rubber washer in two places, one at the edge of the out turned portion 27 and the other at the junction 29 between the portions 16' 100 105

and 25 of the cover. Thus it will be seen that a double shoulder seam is formed which is perfectly safe against accidental removal of the cover but which lends itself to a 5 convenient removal of the cover or cap when desired, this being accomplished by inserting a sharp instrument, such as the tine of a fork, between the cylindrical portion 16' and the container, rupturing the gasket and 10 then pulling out the gasket by one of the broken ends. This pulling elongates the rubber and allows it to pass readily between the shoulder 29 and the container. Since the inside diameter of the cylindrical 15 portion 16' of the cap is greater in diameter than the greatest diameter of the flange 27 the cover 11 may be replaced on the can after part of the contents has been removed thus providing a container 20 having no inturned flanges or obstructions.

The invention lends itself readily to that class of use where the body and one end, usually the removable cover end, are assembled, the can then filled and finally the 25 other end, usually the permanent bottom, applied and secured by a seaming operation.

The flaring of the edge of the body of the container and the slight tapering of the wall of the cap which fits within the container forms a very tight joint, which is 30 useful not only in aiding the permanent sealing of the container, but also permits of the use of the cap as a temporary cover when the gasket has been removed in opening 35 the vessel.

The nearly vertical wall 21 of the cap fits snugly the wall 28 of the can and consequently when the cap is pushed firmly into the container a hermetic seal is formed 40 which is generally known as a compression closure or a friction closure and is a very common closure at the present time for paint cans of smaller sizes. The use of a closure of this kind in combination with a permanent gasket closure is however a novel 45 feature of the present invention.

What I claim is:

1. The method of assembling a container with a cap and a gasket, which consists in 50 placing the cap upon the container, and applying radial pressure to the periphery of the cap to distort the gasket and bead the cap and simultaneously flaring the container wall whereby a double shouldered seam is 55 formed.

2. The method of assembling a container with a cap and a gasket, which consists in applying radial pressure to the cap to pinch the gasket against the container, simultaneously flaring the wall of the container at 60 its edge, and later applying radial pressure to compress the gasket further, and to form a bead upon said cap.

3. The method of assembling a container 65 with a cap and a gasket which consists in

crimping the edge of the cap against the gasket and expanding the edge of the container to form an outward turned flange, and then beading the cap to bind the gasket further, thereby forming a double shoulder seam. 70

4. A seam formed by a wall of a container, a compression closure cap and a gasket characterized by the provision of an outwardly flared rim at the mouth of the 75 container forming an external shoulder, a bead on said cap and a cylindrical portion of less diameter integral therewith and forming therewith a shoulder, said gasket being compressed between the wall of the 80 container, the bead and the cylindrical portion of the cap and between said shoulders.

5. A seam formed by a substantially cylindrical wall of a metal container, a metal cap and a gasket characterized by the provision of an outwardly flared rim on the container forming an external shoulder, an internal wall on said cap contacting with the wall of the container to form a compression closure, an annular flange on said 90 cap, said gasket being compressed against the outer wall of the container and said shoulder by said flange, the inner diameter of said annular flange being greater than the extreme diameter of the flared rim so that said cap may be separated from the container without distortion of either when the gasket has been removed and may be replaced by forcing the internal wall of the cap within the wall of the container 95 thus forming a substantially hermetic closure.

6. A seam formed by a cylindrical wall of a container, a compression closure cap and a gasket characterized by the provision 100 of a flared rim at the mouth of the container forming an external shoulder, a bead on said cap and a cylindrical portion of less diameter integral therewith and forming therewith a shoulder, said gasket being compressed between the flaring wall of the container, the bead, and the cylindrical portion 110 of the cap and between said shoulders.

7. In combination, a substantially cylindrical sheet metal container, a removable 115 and replaceable metal cap slidably and frictionally fitting in part within the container to form therewith a telescoping hermetic seal, a gasket surrounding the outer wall of the container and an annular extension on said cap bearing on the gasket to deform it against the outer cylindrical wall of the container to form a second and independent hermetic seal.

8. In combination, a metal container, a removable and replaceable metal cap therefor, means formed by integral contacting portions of said container and said cap for forming a sliding friction seal, said cap contacting with the container on the inner 120

wall only of the container and additional means including a deformable and non-replaceable gasket for forming a second independent seal on the outside of the container which second seal must be destroyed upon first access to the contents of the container, said cap having an inwardly directed, gasket engaging portion, the inner diameter of which is greater than the extreme outer diameter of the container and less than the outer diameter of the gasket.

9. The combination with a cylindrical metal can and a metal cap therefor, said members providing a seal of the compression closure type in which the contacting surfaces are metal, the engagement is frictional and sliding and the seal hermetic, of a second seal, said second seal including a gasket surrounding the outer wall of the container at the mouth thereof, compressed

radially against the container wall by a portion of the cap, visible between the cap and container, and which must be destroyed before access may be had to the contents for the first time.

10. The combination with a substantially cylindrical metal can and a metal cap therefor, said members providing a seal of the compression closure type in which the contacting surfaces are metal, the engagement frictional and sliding, and the seal hermetic, of a second seal, said second seal including a gasket surrounding the outer wall of the container near the mouth thereof, compressed against the container wall by a portion of the cap, and which must be removed before access may be had to the contents for the first time.

FRANK J. O'BRIEN.
